UNITED STATES PATENT OFFICE.

HARRIETTE ENSLEY HODGSON, OF NEW YORK, N. Y.

CIGARETTE PACKAGE.

Application filed July 10, 1924. Serial No. 725,142.

The invention is a device for cigarette smokers, to avoid the inconvenience of being without a match. It is customary for cigar stores to give a book of paper matches with a package of cigarettes, but nevertheless the smoker frequently finds himself without matches, usually due to the match-book having been mislaid. The object of this invention is to make it possible for a cigarette package and one of these books of matches to be presented to the purchaser in an assembled condition, and to be carried in that condition, the book of matches being readily withdrawn from the package for use and reinserted in a pocket after each use. The invention is likewise applicable to refillable cigarette cases, and both applications of the invention are illustrated herein.

In the accompanying drawings forming a part hereof:

Fig. 1 is a perspective view of a cardboard cigarette box, of the hinged lid type provided with a pocket and entrance for a match-book, which is shown in place;

Fig. 2 is a perspective view of the same box without the match-book, the outer wall of the pocket being shown laid down in the condition in which the packages are shipped;

Fig. 3 is a transverse vertical section with the matches in place;

Fig. 4 is a vertical longitudinal section;

Fig. 5 is a perspective view of a cigarette case embodying the invention; and

Fig. 6 is a perspective view of a paper package of cigarettes embodying the invention.

The cigarette package of Figs. 1 to 4 is a usual form comprising a tray bottom 2 and a hinged top 3. A transverse oblong opening 4 is cut in the top wall near one end of the box, and the cardboard wall for a suitable distance from this slot toward the other end of the box is adapted to be raised at a slight inclination as seen in Figs. 1 and 4. This may be accomplished by cutting the cardboard on parallel lines extending from the opening, and providing pasted paper stay strips 5 outside and/or inside, which permit the wall section 6 to be slightly raised and laid flat, or otherwise. The inside of the pocket is formed by a stout piece of paper or the like 7, which is pasted or otherwise united to the under part of the cover so as to extend with some fullness beneath the wall section 6 and the opening 4,

entirely closing off the pocket and its entrance from the interior of the box.

The pocket thus formed is of the proper size and proportions to receive one of the familiar match books 8, which is inserted through the entrance and slid lengthwise into the pocket, in which position it lies partly above and partly below the top wall, adding practically nothing to the bulk of the package for carrying purposes. The match books are not assembled with the cigarette packages when shipped from the factory, but are put in by the retail tobacconist. The pocket is of such character as to permit the match book to be taken out and slipped back readily by the user, so that the matches are always at hand.

Fig. 5 illustrates a cigarette case 9 of metal or other material provided with a similar pocket in one of its walls. The entrance opening is marked 4^a, the lifted wall section 6^a, and the inside wall, which in this instance need not necessarily close off the opening from the interior of the case, is marked 7^a. The pocket walls 6^a and 7^a may in this case be rigid and fixed.

Fig. 6 shows a cigarette package 10 of the oblong paper bag type. These packages, as is well known, have a complete lining of tin-foil or paper; and the pocket can therefore be obtained by cutting a slit 4^b slightly wider than a match-book, across one of the broad sides of the outer wrapping near one end. The lining, which is not severed, thus forms the inner wall of the pocket, closing it off from the cigarettes. When the match-book 8 is inserted, the flexibility of the wrappings and the yielding nature of the cigarettes causes the match-book to press somewhat into the package, raising the part 6^b of the outer wrapping only slightly, the tension of the outer wrapping binding the book into the package.

While it is contemplated that the best use of the invention will be for the retailer to insert the match-books, it is obvious that the books may be put into the cigarette packages at the cigarette factory if it should be found satisfactory to ship the assemblage. The complete package of cigarettes and match-book may be manufactured by the cigarette manufacturer, by the jobber, or by the retailer, as may be most practical under all the conditions.

What I claim as new is:
A cigarette box comprising a tray bottom

and a hinged lid, said lid having an oblong or slotted entrance opening in its top wall and a section of said wall extending from the opening being severed along two sides from the adjoining portions of the wall, and a flexible connection between said sides and the cover enabling said section to be lifted and laid flat, together with a sheet on the inside of the lid forming the inner wall of a pocket adapted to receive a book of 10 matches lying partly above and partly below the plane of the wall.

HARRIETTE ENSLEY HODGSON.
